(57) **CLAIM**

I claim the ornamental design for a soft case for a lens or telescope, as shown and described.

DESCRIPTION

FIG. 1 is a left side perspective view of a soft case for a lens or telescope according to the present invention;

FIG. 2 is a right side perspective view of the soft case for a lens or telescope of FIG. 1;

FIG. 3 is a front side view of the soft case for a lens or telescope of FIG. 1;

FIG. 4 is a back side view of the soft case for a lens or telescope of FIG. 1;

FIG. 5 is a left side view of the soft case for a lens or telescope of FIG. 1;

FIG. 6 is a right side view of the soft case for a lens or telescope of FIG. 1;

FIG. 7 is a top side view of the soft case for a lens or telescope of FIG. 1; and,

FIG. 8 is a bottom side view of the soft case for a lens or telescope of FIG. 1.

The broken lines in the drawing views depict stitching, which forms no part of the claimed design.
